(57) **CLAIM**

The ornamental design for a dental floss, as shown and described.

DESCRIPTION

FIG. 1 is a perspective view of a dental floss, showing a first embodiment of my new design;

FIG. 2 is a front elevational view of FIG. 1, the rear elevational view being a mirror image thereof;

FIG. 3 is a top plan view of FIG. 1, the bottom plan view being a mirror image thereof;

FIG. 4 is a left-side elevational view of FIG. 1, the right-side elevational view being a mirror image thereof;

FIG. 5 is a cross-sectional view of the dental floss taken in direction of line 5-5 of FIG. 4;

FIG. 6 is a cross-sectional view of the dental floss taken in the direction of 6-6 of FIG. 4;

FIG. 7 is a perspective view of the dental floss shown in a second embodiment;

FIG. 8 is a front elevational view of FIG. 7, the rear elevational view being a mirror image thereof;

FIG. 9 is a top plan view of FIG. 7, the bottom plan view being a mirror image thereof;

FIG. 10 is a left-side elevational view of FIG. 7, the right-side elevational view being a mirror image thereof;

FIG. 11 is a cross-sectional view of the dental floss taken in the direction of line 11-11 of FIG. 10; and,

FIG. 12 is a cross-sectional view of the dental floss taken in the direction of line 12-12 of FIG. 10.

The diagonal broken lines in FIGS. 11 and 12 indicate a cut through a solid, transparent surface.

The broken lines in the figures depict portions of the dental floss that form no part of the claimed design.
